BOTTLE

Elwyn R. Gooding, Ann Arbor, Mich., assignor to
Ex-Cell-O Corporation, Detroit, Mich.

Original design application Apr. 1, 1964, Ser. No. 79,301,
now Patent No. 202,445, dated Sept. 28, 1965. Divided
and this application July 2, 1965, Ser. No. 85,997

Term of patent 3½ years

(Cl. D58—6)

FIG. 1 is a side elevational view of a bottle, showing my new design;

FIG. 2 is an end elevational view thereof;

FIG. 3 is a top plan view thereof;

FIG. 4 is a bottom plan view thereof; and

FIG. 5 is a cross sectional view thereof taken along line 5—5 of FIG. 1.

This application is a division of my earlier filed pending application Serial No. D.79,301, now design Patent No. D.202,445.

The dominant features of my design reside in the portions shown in full lines.

I claim:

The ornamental design for a bottle, as shown and described.
